UNITED STATES PATENT OFFICE.

EDWIN E. SLICK, OF PITTSBURGH, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A TUMBLER OR SIMILAR ARTICLE.

Application filed May 29, 1929. Serial No. 31,462. Term of patent 14 years.

To all whom it may concern:

Be it known that I, EDWIN E. SLICK, a citizen of the United States, residing at Pittsburgh, in the county of Allegheny and State of Pennsylvania, have invented a new, original, and ornamental Design for Tumbler or Similar Article, of which the following is a specification, reference being had to the accompanying drawing forming a part thereof, in which the figure is a perspective view of a tumbler, showing my new design.

I claim:

The ornamental design for a tumbler or similar article, as shown.

In witness whereof, I have hereunto set my hand.

EDWIN E. SLICK.
